PARTY-LINE TELEPHONE SYSTEM.

1,093,041.

Specification of Letters Patent. Patented Apr. 14, 1914.

Application filed November 15, 1906. Serial No. 843,568.

To all whom it may concern:

Be it known that I, CHARLES J. ERICKSON, a citizen of the United States of America, and resident of Chicago, Cook county, Illinois, have invented a certain new and useful Improvement in Party-Line Telephone Systems, of which the following is a specification.

My invention relates to telephone exchange systems employing subscriber-controlled switches for trunking or extending calling lines into connection with called lines, and in which a plurality of telephones are employed on one line, such arrangements being commonly known as extension or party-lines.

In application Serial No. 299,268 there is shown a common battery lock-out system for preventing interference between subscribers on the same extension or party-line.

An object of my invention is to provide improved means for preventing interference between subscribers on the same line in an automatic system employing a common battery or centralized source of talking current.

It is also an object to provide certain novel features and details of construction and combinations tending to increase the general efficiency of a telephone system of this particular character.

To the foregoing and other useful ends, my invention consists in matters hereinafter disclosed and claimed.

In the accompanying drawings Figure 1 is a diagram showing two party-lines (#110 and #120) connected through a central station. One of the said party-lines is provided with two substations (A and F) that are bridged across the line conductors in multiple; and the other party-line is also provided with similar substations, one of which is shown at H. One of said lines is shown connected through a first-selector C and a connector D with the other said party line, which latter has bridged across it a first-selector E. The substations A, F and H in Fig. 1 are similar, as well as the first-selectors C and E. A central battery B is shown having its positive terminal preferably grounded at G. Fig. 2 is a diagram of a substation K differing from the substation F only in the connections of the locking relay.

The substations may be of any suitable or approved type, for instance of the general

type shown in patent application Serial No. 278,901. The substations are provided with the usual details essential to subscribers' substations of the class in question. The substation A, for instance, is provided with a receiver 2 and switch-hook 3, which latter has radiating from its body a number of cam arms 4, 5 and 6, said hook being pivotally secured to the keyboard frame (not shown) by a screw 7 about which it swings when the receiver is removed. This motion is produced for the purpose of changing certain switching operations to be disclosed. Furthermore, said substation has a transmitter 8, a ringer 9, an induction-coil 10 having a primary winding 11 and a secondary winding 12, a condenser 13, impulse wheel 14 which has the usual vertical impulse teeth 15 that are adapted to operate the vertical impulse spring 16. In addition, the impulse wheel carries a rotary impulse tooth 17 which operates the rotary impulse spring 18. The cam arm 4 controls the so-called locking arm 19 in such a manner that when the switch-hook rises, and before the dial is rotated, the insulating tip 20 upon the end of the locking cam arm 19 that normally rests on the front end of the spring 21 is driven to the inner edge of the angled section of the ground spring 21, whereby when the dial is rotated by the calling subscriber the pin 22 upon the end of the locking dog 23 is able to pass beneath the locking cam to raise the said cam a trifle, causing the said insulating tip 20 to fall behind the said angled section of the ground spring 21, and permitting the said spring, before, to make contact with a cooperating ground spring 24.

The engagement of the ground springs 21 and 24, by the operation described, places the ground post 25 in connection with the substation ground G, whereby when the subscriber releases the dial after rotating it, as described, the vertical impulse teeth 15 will cause the vertical impulse spring 16 to come in contact with the ground post 25; and immediately after, the rotary impulse tooth 17 causes the rotary impulse spring 18 to come in contact with the same ground post 25. When the switch-hook is down the cam arm 6 maintains the switch springs 26 and 27 in contact, thereby bridging the ringer 9 in series with the condenser 13 across the line. The springs 28 and 29 are

then disengaged and the primary winding 11 in series with the transmitter 8 is removed from across the line. Even after the switch-hook is raised, since the finger 30 of 5 the cam dog 23 controls the engagement of the said springs 28 and 29, and since the said cam dog rotates in unison with the dial, if the dial is rotated the springs 28 and 29 and, therefore, the subscriber's line conductors are kept separated. The signaling device whereby a subscriber may signal another after a connection has been established 10 comprises a push-button 31 and spring 32, which latter normally engages the contact point 33; but when the push-button 31 is pressed, the spring 32 leaves the contact point 33 and engages the contact point 34 which is connected to the substation ground G¹. The means whereby the subscriber 15 may release the central station apparatus brought into service comprises three springs 35, 36 and 37 commonly known as release springs, and so controlled by the cam arm 5 that when the switch-hook descends the three release springs are brought into contact, thereby grounding both sides of the subscriber's line simultaneously. In addition, the substation is provided with a lock-out relay 38 connected in parallel or shunt 20 with the primary winding 11 of the induction-coil 10. The substation K shown in Fig. 2 is similar to the substations A, F and H. The locking relay 194, however, is shown connected in parallel or shunt with both the primary winding 195 and the transmitter 196. Said relay is provided with an armature 39 pivoted at 40, and its non-pivoted end is formed into a hook bent at right angles to the armature. Said hook is 25 adapted to engage an eye 41 on the locking dog 23 when the lock-out relay 38 becomes energized, thereby locking the said dog in normal position; and since said dog is rigidly connected to the dial, the latter is also 30 locked against operation by the subscriber. The armature 39 is retained in normal position by the retracting spring 42.

The first-selector switch shown at C may 35 be of any suitable or approved type, for instance of the general type described in Patent No. 815,321, granted March 13, 1906, to Keith, Erickson and Erickson. Among other details it embodies the following well-known devices and circuits: The switch-shaft (not shown) carries the vertical and 40 rotary wipers 43 and 44, respectively, and the private wiper 45. The side switch is well known and comprises the side switch wipers 46, 47, 48 and 49, which may be 45 designated as the vertical, rotary and private side switch wipers, and the rotary magnet wiper, respectively. The side switch is under the control of the private magnet 50, and in the normal or first position of the 50 side switch the wipers 46, 47, 48 and 49 oc-

cup the contact points 51, 52, 53 and 54, respectively. In the second position they rest on the contact points 55, 56, 57 and 58, respectively, and in the third position the contact points 59, 60, 61 and 62 are engaged 70 by their respective wipers. Through the medium of the vertical line relay 63, and while the side switch is in first position, the subscriber controls the vertical magnet 64, which latter operates to raise the switch-shaft and wipers 43, 44 and 45 vertically. By means of the rotary line relay 65, and while the side switch is in first position, the subscriber controls the private magnet 50 and, therefore, the side switch. While 75 the side switch is in second position the rotary magnet 67, which operates the switch-shaft and wipers 43, 44 and 45 in a rotary direction, is energized. The vertical and rotary line relays 63 and 65, acting 80 jointly, provide the means whereby the subscriber controls the release magnet 68 while the side switch is in first or second position. If the side switch passes to third position, then, since the selector C is of the 85 trunk-release type, the selector is controlled through the next switch, with which latter a connection is established through the private wiper 45 and by means of the back-release relay 69. The bridge-cut-off relay 90 70 is provided to open the connection between the line relays 63 and 65 and between said relays and battery B when the line to which the switch C belongs is called. This is desirable, because if the relays are not 95 disconnected from each other and battery, the ringing current for signaling the subscriber may operate either or both of the relays 63 and 65 and cause some interference with the called switch. It is also desirable 100 to remove the bridge formed through the said relays from across the line, so as to give the voice-currents as clear a path as possible. 105

The function of the private normal relays 71 and 72 is to control a connection between the private normal conductor 133' and the side switch wiper 48 for the purpose of removing the guarding potential at the connector D when one subscriber is calling another back over his own line. By referring 110 to Fig. 1 it will be seen that this connection is always maintained except when the relay 71 is at normal and the relay 72 is energized. Across the terminals of the private normal relays 71 and 72 are bridged the condensers 115 73 and 74, respectively, to increase the efficiency of the talking circuit. The private normal relays 71 and 72 are provided with armatures 75 and 76 and insulating bushings 77 and 78, respectively, to serve as means for 120 controlling the connections described. The connector switch D may also be of any suitable or approved type, and, as shown, is an improved form of the connector described in Patent No. 815,176, granted March 13, 1906, 125 130

to Keith, Erickson and Erickson. The mechanical details of the selector and connector, as is well known, are very much the same, although there is some material difference in the circuits. For instance, the connector switch-shaft (which is not shown) carries, like the selector, the line wipers 79 and 80 and the private wiper 81. The connector switch is also controlled by the calling subscriber through the medium of the vertical and rotary line relays 82 and 83. The vertical line relay 82 directly controls the vertical magnet 84 and also the rotary magnet 85. The office of the vertical magnet 84 is to give the shaft and shaft wipers a vertical motion, and the rotary magnet 85 imparts to the shaft and wipers a rotary or circular motion. The rotary line relay 83 controls the private magnet 86, which latter under certain conditions in turn controls the vertical and rotary magnets 84 and 85, the release magnet 87, and also the side switch wipers 88, 89, 90, 91 and 92. The side switch, like the side switch of the selector, has a normal or first position, a second position and a third position. The release magnet 87 is also controlled by the vertical and rotary line relays 82 and 83 conjointly. By the use of the condensers 93 and 94 the connector divides the line circuit through it into two inductively connected sections. The connector is provided with a differentially wound relay 95 which is composed of the windings 96 and 97. The function of this coil is to control the ringer relay 97, by means of which the ringer generator 98 is bridged across the terminals of the called line to signal the called subscriber, and through the medium of which relay 97 the release magnet 87 is controlled after the called subscriber answers. The back-bridge relays 99 and 100 provide the called subscriber with talking battery current when his primary circuit is bridged across the line. The central station is equipped with the busy signaling apparatus I of any suitable design, as, for example, the one comprising an interrupter 101 in series with the primary winding 103 of the induction-coil 102, where by a busy signaling current is induced in the secondary winding of the said induction-coil 102. The secondary winding 104 is connected with the side switch wiper 90. The first selector E of the called line is the same as the first-selector C and, therefore, the description of the selector C is applicable. The substation II, like the station F is, of course, a duplicate of substation A and, therefore, requires no description.

60 The calling operation by which the subscriber A, for example, would call and signal subscriber II is as follows: To call the number 120, which is arbitrarily chosen as the number of the substation II, the subscriber A at substation #110 operates his calling de-

vice in a suitable manner corresponding to each digit. For each digit the vertical line is grounded a certain number of times corresponding to the numerical value of the digit, and then the rotary side of the line is grounded once. The receiver 2 is removed from the switch-hook 3, closing in contact the springs 28 and 29 and breaking the contact between springs 26 and 27, thus removing the ringer 9 from across the line and bridging instead the transmitter circuit. The cam arm 4 raises the locking arm 19, as previously described. The first digit being 1 the subscriber at substation A turns his dial for the first digit 1, thereby grounding the vertical line conductor 105 once and the rotary line conductor 106 once upon the return motion of the dial. When the dial is pulled the pin 22 upon the end of the locking dog 23 passes beneath the locking cam, causing the tip 20 to fall behind the angled section of the ground spring 21, as previously described, thus placing the ground post 25 in connection with the substation ground G¹. Grounding the vertical line conductor 105 once energizes the vertical line relay 63 of the first-selector. The circuit through said vertical line relay extends from ground G¹ through the ground springs 21 and 24 to the ground post 25, thence to the vertical impulse spring 16, vertical line conductor 105 to the side switch wiper 46, contact point 51, through the vertical line relay 63 to the bridge-cut-off springs 106' and 107 (the bridge-cut-off springs being normally in contact) to the battery lead 108, thence through battery B to ground G.

65 Each time that the vertical line relay 63 is energized the vertical line relay springs 109 and 110 are pressed into contact and an energizing circuit is each time established through the vertical magnet 64. The circuit through said magnet extends from ground G² to the relay springs 110 and 109, to the private magnet springs 111 and 112, through the winding of the vertical magnet 64 to the battery lead 108, thence through battery B to ground G. The vertical magnet 64 being operated once, the first-selector switch-shaft and wipers 43, 44 and 45 are raised one step. The said wipers are carried to a level with the contact points that constitute the terminal of the trunk line leading to the connector switch D. Following the vertical impulse the rotary impulse spring 18 is grounded once by the rotary impulse tooth 17, thereby grounding the rotary line conductor 106 once and energizing the rotary line relay 65. The path of this energizing circuit is from ground G¹ through the ground springs 21 and 24 to the ground post 25, rotary impulse spring 18 to the rotary line conductor 106, side switch wiper 47, contact point 52 to the rotary line relay 65, thence to the bridge-cut-off springs 113, 106' and 107 to the

battery lead 108, thence through battery B and to ground G. The rotary line relay upon energizing presses the line relay springs 114 and 110 into contact, thereby closing an energizing circuit through the private magnet 50. The current through said magnet passes from ground G² through the springs 110 and 114 to the private magnet 50 and battery lead 108, thence through battery B and to ground G. The private magnet being energized for a moment the side switch of the first-selector passes to second position, permitting the side switch wiper 49 to close the energizing circuit through the rotary magnet 67. The current flows from ground G³ through contact point 58, side switch wiper 49 to the interrupter springs 115 and 116, thence through the winding of the rotary magnet 67 to the battery lead 108, thence through battery B and to ground G. The rotary magnet is energized one step and the shaft wipers 43, 44 and 45 are carried into engagement with the bank contacts that constitute the terminal of a trunk line leading to the connector switch D. If the first trunk line is busy an energizing circuit is established through the private magnet 50, when the private wiper 45 strikes a grounded contact, thereby retaining the side switch in second position and maintaining the circuit through the rotary magnet 67. The rotary magnet by intermittent magnetization causes the shaft wipers to rotate past the last busy trunk line. However, as soon as the private magnet deenergizes the side switch is tripped into third position, or if there are no busy contacts to be passed over, the rotary magnet 67, as is well known, trips the side switch to third position, when the wipers engage the first trunk line, with the result that as soon as the side switch wipers 46 and 47 engage their respective contacts 59 and 60, the subscriber's line is extended to the connector switch D. Also, since the side switch wiper 48 engages the grounded contact point 61, a guarding potential is established at the private wiper 45 for protecting the seized trunk line at the connector D from being molested by any other switch. This guarding potential also protects the calling line by establishing a guarding potential at the connector bank over the private normal conductor 117. The second digit is called after the subscriber has established connection with the connector D by way of the trunk conductors 118 and 119. The subscriber rotates the dial, as described, for the second digit 2, thereby grounding the vertical and rotary line conductors 105 and 106 which causes the energization of the connector vertical and rotary line relays 82 and 83, and also of the differential relay 95. The energizing current flows over the following path: from ground G¹ to the vertical line conductor 105, to the side switch wiper 46, contact

point 59, through the winding of the private normal relay 71, shaft wiper 43 to the trunk conductor 118, through the winding of the vertical line relay 82 and winding 96 of the differential coil 95 to the battery lead 108, thence through battery B to ground G. Each time the vertical line relay 82 is energized the line relay springs 123 and 124 are pressed into contact and an energizing circuit is each time established through the vertical magnet 84. The energizing of the differential relay 95 is of no consequence at this time. The energizing current through the vertical magnet 84 flows from ground G⁴ to the springs 123 and 124, private magnet springs 125 and 126 to the vertical magnet 84, contact point 127, side switch wiper 88 to the battery lead 108, thence through battery B to ground G.

Each time that the vertical magnet 84 is energized it raises the shaft and wipers 79, 80 and 81 one step at a time until the said wipers are carried two steps to a level in which are located the terminal contacts of the line #120. When the rotary line conductor 106 is grounded the rotary line relay 83 and the differential relay 95 become energized through the following path: from ground G¹ to the rotary line conductor 106, side switch wiper 47, contact point 60, through the winding of the private normal relay 72, shaft wiper 44, trunk conductor 119, through the winding of the rotary line relay 83 and winding 97 of the differential relay 95 to the ringer relay springs 120 and 121 (which are normally in contact), and to battery lead 108, thence through battery B and to ground G. The energization of the rotary line relay 83 causes the springs 128 and 123 to come into contact, thereby completing a circuit through the private magnet 86. The path of the energizing circuit is from ground G⁴, line relay springs 123 and 128, through the winding of the private magnet 86 to the ringer relay springs 120 and 121, to the battery lead 108, thence through battery B and to ground G. The momentary energization of the private magnet 86 causes the release of the side switch from first to second position, thus placing the side switch wipers 88 and 89 in contact with the points 129 and 130, respectively. The last digit being 0 the subscriber operates the dial, as previously described, grounding the vertical line conductor 105 ten times and the rotary line conductor 106 once. The vertical and rotary line relays 82 and 83 are operated over the previously traced circuits. However, when the line relay springs 123 and 124 engage, a circuit is closed through the rotary magnet 85 instead of through the vertical magnet 84. The circuit may be traced from ground G⁴ to the line relay springs 123 and 124, through springs 125 and 126, through the rotary

magnet 83, contact point 129, side switch wiper 88 to the battery lead 108, thence through battery B to ground G. Each time that the rotary magnet is energized the rotary armature is attracted and rotates the shaft carrying the wipers 79, 80 and 81 one step at a time until the said wipers are carried into engagement with the normal conductors 131, 132 and 133 that lead to the line of the desired subscriber whose number is 120. The energization of the rotary line relay 84, as previously stated, completes an energizing circuit through the private magnet 96, which now operates with one of two results, namely the release of the side switch from second to third position, or the so-called busy release of the connector, which will be described. Suppose the former results to occur and the side switch to pass to third position, placing the side switch wipers 88, 89, 90, 91 and 92 in contact with the points 134, 135, 136, 137 and 138, respectively. An energizing circuit through the ringer relay 97 is immediately established from ground G to contact point 135, side switch wiper 89 to the ringer relay 97, then to the differential relay springs 139 and 140 to the contact point 134, side switch wiper 90 to the battery lead 108, thence through battery B and to ground G. The energization of the ringer relay 97 extends the normal conductors 105 and 106 of the calling subscriber to the normal conductors 131 and 132 of the called line. Furthermore, when the side switch passes to third position a guarding potential is established for the subscriber of the called line. This guarding potential extends from ground G to the side switch wiper 89, thence to the shaft wiper 81 which now engages the private contact of the selector E. The said guarding potential is then established through the bridge-wiper 81, further more, causes the side switch to pass through the bridge-wiper 81, from the said private contact of the selector E, through the private normal conductor 133, across springs 166 and 167, conductor 158, side switch wiper 48 to the bridge-wiper 70, thence to the battery lead 108, and through battery B to ground G. The said relay then operates to separate the springs 166, 167 and 137 for destroying the bridge normally formed through the line conductors 132 and 131 of the selector E.

To signal the called subscriber the calling subscriber passes the signaling button 31, placing the spring 41 in contact with the subscriber ground 41, thereby energizing the vertical line relay 82 over a path previously traced.

It should be observed that the ringer relay springs 141 and 142 are normally in contact with the springs 143 and 144, respectively, of which is connected the ringer generator J. Therefore, when the side switch is in third position, if the ringer re-

lay were not energized, ringing current would pass out over the called subscriber's line conductors 131 and 132, since the vertical and rotary side switch wipers 91 and 92 are then directly connected with the line wipers 79 and 80, respectively. It is for this reason that special provision has been made for the ringer relay springs 141 and 142, to separate them from the ringer relay springs 143 and 144 at the instant that the side switch passes into third position. Furthermore, when the vertical line relay 82 becomes energized the differential relay 95 is also energized through the winding 96. The armature is attracted and the springs 140 and 139 are separated, thereby breaking the continuity of the energizing circuit through the ringer relay 97; and as a result the ringer relay becomes deenergized, thus allowing the springs 141 and 142 to fall back into contact with the ringer generator springs 143 and 144, respectively. As a result, ringing current is then permitted to pass out on the line of the called subscriber, which current passes through his ringer and signals him. This signaling current passes from the generator J to the springs 143 and 141, side switch wiper 91, contact point 137, shaft wiper 79, normal conductor 131, vertical line conductor 145, condenser 146, ringer 147, springs 148 and 149 to the rotary line conductor 150, normal conductor 132, shaft wiper 80, contact point 138, side switch wiper 92, ringer relay springs 142 and 144 and back to the generator J. As soon as the calling subscriber releases his signaling button 31 the current through the differential relay 95 is interrupted, deenergizing the differential relay. The springs 139 and 140, upon reengaging, reestablish the energizing circuit through the ringer relay 97, which latter upon attracting its armature severs the connection between the generator J and the called line. As the called subscriber removes his receiver 168 from the switch-hook 170 the latter, upon rising, destroys the ringing circuit through the bell 147 at the instant the springs 148 and 149 separate. The switch-hook also forces the primary circuit springs 151 and 152 into contact, closing a circuit through its own station that provides the transmitter 153 and the primary winding 154 of the induction-coil 155 with current for talking purposes. The current for this circuit passes from ground G to the side switch wiper 89, to the coil 100, ringer relay springs 157 and 142 to the side switch wiper 92, rotary line wiper 80, conductors 132 and 150, primary winding 154 of the induction-coil 155, transmitter 153, springs 152 and 151 to the vertical line conductor 145, conductor 131, vertical line wiper 79, side switch wiper 91, ringer relay springs 141 and 159 to the back-bridge coil 130.

99, thence to the battery lead 108, and through battery B to ground G.

It will be noticed by referring to the drawing that the lock-out relay 171 is connected in parallel or shunt with the primary winding 154 of the induction-coil 155; hence when current flows in the primary winding 154 a part is shunted through said relay, thus energizing the lock-out relay which attracts its armature 172, which latter in turn engages the locking dog 173, thus rendering the calling device inoperative. The energizing current for the talking circuit, in passing through the coil 100, energizes said coil and causes the armature to close in contact with the springs 160 and 161. At the instant these two springs 160 and 161 engage, the calling substation is provided with current for energizing or charging the talking apparatus. The circuit in this case extends from ground G⁵ to the side switch wiper 89, to the relay springs 160 and 161, ringer relay springs 162 and 120, through the winding 97 of the differential relay 95, rotary line relay 83, conductor 119, first-selector shaft wiper 44, relay 72, side switch wiper 47 to the rotary line conductor 106, primary winding 11 of the induction-coil 10, transmitter 8, springs 29 and 28 to the vertical line conductor 105, side switch wiper 46 to the private normal relay 71, shaft wiper 43, conductor 118, vertical line relay 82, through the winding 96 of the differential relay 95, thence to the battery lead 108 and through battery B to ground G. Since the lock-out relay 38 is placed around the primary winding 11, the said relay becomes energized and attracts its armature 39 and locks the calling device of the substation #110 while current is flowing in the above circuit.

It will be noticed that the two windings 96 and 97 of the differential relay 95 are included in the circuit that provides the calling subscriber with talking current. These two windings are so arranged that when the current passes through them in this manner the differential relay 95 does not energize. Since the talking circuit current to the calling subscriber passes through the vertical and rotary line relays 82 and 83, as soon as the said circuit is established, these two relays become energized and attract their respective armatures, thereby placing the release springs 156 and 163 in contact. This would result in the release of the connector were it not for the fact that the connection between the release magnet 87 and the non-grounded battery terminal is interrupted between the ringer relay springs 120 and 121, while the ringer relay 97' is energized. Furthermore, the private normal relays 71 and 72 of the first-selector become energized, placing the springs 164 and 165 in contact 65 and separating the springs 166 and 167. This,

however, in no way removes the guarding potential established at the connector bank for the protection of the calling line. Under these conditions the primary windings 11 and 154 of the substations #110 and #120, respectively, are connected in series in a circuit shown in heavy lines in Fig. 1, through the condensers 73, 93, 94 and 74. The receivers 2 and 168 of the two substations in question are in series, each in a local circuit with their respective secondary windings 12 and 169 of their induction-coils 10 and 155, and in a well-known and familiar manner the two subscribers may communicate with each other, since their primary circuits are charged with a suitable current from the central or common battery B.

An intruding subscriber is prevented from interfering with or molesting an established connection. Suppose the subscribers A and H are in connection over the circuit previously described, and the subscriber F (who occupies the line in common with A) removes his receiver 158 from the switch-hook 174, thereby bridging his primary circuit including the primary winding 175 and transmitter 176 across the line. Immediately, the lock-out relay 177 becomes energized, attracting its armature 178, which latter engages the locking dog 179, thereby rendering the calling device at substation F completely inoperative both for switching and signaling purposes. The substation locking dog is prevented from turning, and from connecting the substation ground release spring and signaling button and ground post through the ground springs. Therefore, the subscriber F can in no possible manner interfere to disconnect or destroy the established connection. The subscriber F upon hanging up his receiver 158 removes the primary winding 175 from across the line; consequently the lock-out relay 177 becomes deenergized and the armature 178 and the locking dog 179 disengage, whereby the substation F becomes operative when the established connection is destroyed.

The front release occurs when the calling subscriber restores his receiver 2 to the switch-hook 3, thereby pressing the release springs 35, 36 and 37 into engagement, which engagement places the line conductors 105 and 106 in connection with the substation ground G¹. The grounding of the rotary line conductor 106 produces a cessation of the flow of current through the rotary line relay 83 and the winding 97 of the differential relay 95. This is brought about by short-circuiting these two windings in series through ground. The short-circuit extends from ground G¹ to the rotary line conductor 106, side switch wiper 47, contact point 60, winding of the relay 72, shaft wiper 44, trunk conductor 119 to the 130

- 5 rotary line relay 83, winding 97 of the differential relay 95 to the ringer relay springs 120 and 162, springs 161 and 160 to the side switch wiper 89 and to ground G². The 10 rotary line relay becomes deenergized and the trunk release spring 163 recedes from the spring 156, and since only the winding 96 of the differential relay 95 is receiving current the said relay becomes energized. 15 The current-flow through the said relay extends from ground G¹ to the release springs 37, 36 and 35, to the vertical line conductor 105, side switch wiper 46, contact point 59, through the winding of relay 71, shaft wiper 15 43, trunk conductor 118, vertical line relay 82, winding 96 of the differential relay 95 to the battery lead 108, then through battery B to ground G.
- 20 The energization of the differential relay 95, as above, produces a deenergization of the ringer relay 97', which latter upon restoring its armature to normal position permits the ringer relay springs 162 and 120 to disengage and the spring 120 to come in contact with the spring 121. The engagement of the springs 120 and 121 again completes an energizing circuit through the winding 97 of the differential relay 95, and current in this way passes through said windings in 25 such a direction as to reinforce the winding 96. Therefore, even after the ringer relay becomes deenergized the differential relay continues to remain magnetized as long as the release springs 35, 36 and 37 remain in 30 contact. The magnetizing current through the winding 97 of the differential relay 95 passes from ground G¹ to the rotary line conductor 106, through the relay 72 to the rotary line relay 83, winding 97 to the ringer 35 relay springs 120 and 121, to the battery lead 108, thence through battery B and to ground G. Furthermore, at the instant that the 40 said ringer relay springs resume their normal position, and simultaneously with the reenergization of the rotary line relay 83 of the connector, the trunk release springs 156 and 163 engage, thus completing an energizing circuit through the release magnet 87 of the connector and the back-release relay 69 of the 45 first-selector, releasing said switches and thus restoring them to normal position and in readiness for further use. The energization of the back release relay 69 of the first-selector causes the springs 183 and 184 50 to engage, thereby completing an energizing circuit through the release magnet 68. It is evident that as soon as the connector wiper 81 is removed from the point with which it has been in engagement, the bridge- 55 cut-off relay 70' of the first-selector E resumes its normal position, leaving the first-selector in condition to be operated by the 60 substation #120. At the same time that the private wiper 81 leaves its contact point 65 the line windings 79 and 80 also leave their

contact points; and as a result the circuit conveying talking current to the substation #120 is also destroyed, at the same time causing the deenergization of the relay 100 and the separation of the springs 160 and 70 161, thereby interrupting the circuit through which current flows through substation #110 for talking purposes.

75 It has been found in practice that good results are obtained when the substation relays 38, 177 and 171 are wound to a resistance of five hundred ohms each.

The busy release follows as a result of the energizing of the rotary line relay 83, if the called line is busy, as follows: The said relay 83, upon energizing, energizes the private magnet 86, as previously stated, which latter in turn presses the springs 180 and 181 into contact. As soon as the said springs engage, the release magnet 87 is then 80 placed in connection with the private wiper 81 (since the side switch wiper 89 is now in second position and in engagement with the contact point 130), which wiper had previously been rotated onto a grounded contact. As a result a flow of current is sent through the release magnet from the grounded wiper 81 to the side switch wiper 89, contact point 130, private magnet springs 181 and 180 to the release magnet 87, ringer 85 relay springs 120 and 121 to the battery lead 108, thence through battery B and to ground G. The release magnet 87 upon energizing releases the connector switch-shaft and restores the connector side switch to 105 first position, returning the vertical magnet 84 to the control of the vertical line relay 82. Therefore, now that the calling subscriber grounds the vertical line conductor 105 to signal, instead of operating the ringer 108 relay he operates the vertical line relay 82, which latter in turn operates the vertical magnet 84. The vertical magnet raises the switch shaft so that the normal post arm 182 permits the spring 183' to engage the 110 contact point 184', thereby permitting a busy signaling current to pass to the calling subscriber's station over the following circuit: from the secondary winding 304 of the busy machine I through the side switch 115 wiper 90, to the contact point 184', spring 183', condenser 94, connector trunk conductor 119, first-selector shaft wiper 44, condenser 74, contact point 60, side switch wiper 47, rotary line conductor 106, primary 120 winding 11 of the induction-coupler transmitter 8, contact point 33, spring 32 to the springs 29 and 28, vertical line conductor 105, side switch wiper 46, contact point 59 to the condenser 73, first-selector shaft wiper 43, connector trunk conductor 118, condenser 93, back-bridge relay 99 to the 130 battery lead 108, thence to the busy machine I. The calling subscriber upon hearing the busy signal will understand that the desired 135

line is in service and will release the switching apparatus by hanging up his receiver.

To call any subscriber not on his own line the calling subscriber will bring about the operation as described in the preceding; but a subscriber like subscriber at substation A may also call another subscriber on his own line. For instance, suppose the subscriber A desires to signal a subscriber occupying the same line, as at F. In this case the calling and called lines are identical, but special provision is made in the first-selector switch to momentarily remove the guarding potential established at the connector bank, and thus allow a subscriber to call back on his own line. When the last rotary impulse is sent over the line the private normal relay 72 becomes energized; thus the springs 166 and 167 disengage and remove the guarding potential from the connector bank. Therefore, this impulse to the rotary line removes the potential which would cause the busy release of the connector, providing the guarding potential still existed, and sends the connector side switch to third position. It is evident, therefore, that a subscriber calling another subscriber on his own line would never get a busy release. The subscriber A having connected the switching apparatus at the central station with his own line, then by pressing the signaling button a suitable number of times sends signaling current impulses out on his line, ringing the different substation bells which are bridged across the called line. The subscriber at F recognizes his substation signal (two rings, for instance) and removes his receiver from the switch-hook. The energization of the relays which places talking current on the circuit is brought about by the substation A at the instant the primary circuit is bridged across the line after the call is completed and, therefore, when the dial returns to normal and closes the springs 28 and 29, after the last rotary impulse has been sent in. Thus it will be seen that any subscriber may call his own line, inasmuch as the connector switch D used in this case will not be automatically released as soon as it engages the multiple line terminal connected with the line from which the call comes. Furthermore, if one subscriber on a party line is using the line no other subscriber on the same line can use the line for either signaling or switching purposes. In other words, the two subscribers who are conversing over the line are safe from intrusion or molestation to this extent, namely that no other subscriber can use the line for switching or signaling purposes, nor can any other subscriber on the same line so operate his telephone or calling device as to endanger the continuity of the circuit established between the two subscribers who

are talking. It is always undesirable, of course, to have it possible for one subscriber on a line to listen-in and hear the conversation conducted over the line by some other subscriber, but in an automatic or semi-automatic system I deem it of far greater importance to provide against the breaking by a third subscriber of a circuit already established between two other subscribers; for while such listening-in may be a source of more or less annoyance, it is evident that this is not so important a consideration as is the maintenance of an established talking circuit. Subscribers may tolerate listening-in, objectionable though it is, but any situation in which a party-line subscriber could not use his telephone without guarantee against interference on the part of other subscribers on the line would not be tolerated. It is evident, however, that my improved lock-out arrangement and devices are of a character to prevent the subscriber from transmitting any signal and from accomplishing the closure of any circuits at the central station.

As indicated in Fig. 1, when the subscriber #110 wishes to call the subscriber F on his own line, the connector D makes connection with the contact points 79', 80' and 81'. The normal conductors 131' and 132' lead back to the line of the calling subscriber, so that when the connector completes the connection it is connected back with the calling line. It will be clear, however, that the guarding potential placed at the connector private bank contact 81', when the selector C first comes into use, is removed when the calling subscriber grounds the rotary line conductor 106. Grounding the rotary line conductor 106, it has been explained, energizes the rotary line relay 83 of the connector D through the private normal relay 72 of the selector C; and, as a result, when the said relay energizes, the springs 166 and 167 are separated, and the guarding potential to the private normal conductor 133' from ground G⁶ is removed to permit the connector side switch to pass to third position. When the subscriber #110 connects with the subscriber H of a different line, the talking current for the substation A passes through both private normal relays 71 and 72, and both of said relays pull up simultaneously; but in that event the guarding potential is not removed, since the circuit destroyed between the springs 166 and 167 by the relay 72 is restored at a point between the springs 164 and 165 by the relay 71. The same is true of the said relays when the subscriber A calls the subscriber F; but this does not occur until after the connector side switch passes to third position, so that there is no interference from such operation.

With reference to the energizing circuit 130

for the substation relay, it will be evident that said relay may be connected in shunt or parallel with the primary winding of the induction coil, as the relay 38 is shown connected in Fig. 1, or it may be in shunt of both the primary winding and the transmitter, as shown in Fig. 2, in which the relay 194 is connected in shunt with both the winding 195 and the transmitter 196. With such a connection the substation relay 194 would receive a stronger energizing current. In either case, however, the relay is in the main line circuit, but not in the talking or voice-current circuit. The connectors, and also the second and third selectors if any, can be employed on a percentage basis, and may thus be less in number than the subscribers. The first-selectors can also be reduced to a percentage basis in any suitable or known manner. In this way automatic trunking is afforded between lines using common battery transmitters and dial locks for preventing interference between party-line subscribers on the same line.

What I claim as my invention is:—

1. In a telephone exchange system, the combination of automatic means for trunking between calling and called subscribers, a telephone line, a plurality of calling dials on said line, a common battery for furnishing switching and talking current to said line, means for bridging the battery across the line, a locking magnet for each dial, and means for preventing bridging of the battery across the said telephone line until after the line calls or is called, said magnets bridged across the line.

2. A subscriber's calling dial, a telephone line, a dial-locking magnet bridged across the line, a common battery, means for bridging said battery across the line to energize said magnet, and impulse-transmitting means responsive to the operation of said dial.

3. A subscriber's calling dial, a telephone line, a telephone bridged across the line, a dial-locking magnet bridged across the line, a common battery, means for bridging said battery across the line to charge the telephone and energize said magnet, and impulse-transmitting means responsive to the operation of said dial.

4. A subscriber's telephone, a calling dial associated with said telephone, a telephone circuit, a dial-locking magnet, subject to control by other subscribers, connected in a parallel branch or shunt of said circuit, and impulse-transmitting means responsive to the operation of said dial.

5. A subscriber's rotatable calling dial, an induction-coil, a dial-locking magnet connected in shunt or parallel with a winding of said coil, and impulse-transmitting means responsive to the operation of said dial.

6. A subscriber's rotatable calling dial, an induction-coil, a dial-locking magnet connected in shunt or parallel with the primary winding of said coil, and impulse-transmitting means responsive to the operation of said dial.

7. A subscriber's rotatable calling dial, an induction-coil, a telephone transmitter connector in series with the primary of said coil, a dial-locking magnet connected in parallel or shunt with the said transmitter and primary, and impulse-transmitting means responsive to the operation of said dial.

8. A subscriber's rotatable calling dial, an induction-coil, a dial-locking magnet connected in shunt or parallel with a winding of said coil, a common battery or centralized source of talking current for energizing said magnet, and impulse-transmitting means responsive to the operation of said dial.

9. A subscriber's rotatable calling dial, an induction-coil, a dial-locking magnet connected in shunt or parallel with the primary winding of said coil, a common battery or centralized source of talking current for energizing said magnet, and impulse-transmitting means responsive to the operation of said dial.

10. A subscriber's rotatable calling dial, an induction-coil, a telephone transmitter connected in series with the primary of said coil, a dial-locking magnet connected in parallel or shunt with the said transmitter and primary, a common battery or centralized source of talking current for energizing said magnet, and impulse-transmitting means responsive to the operation of said dial.

11. A subscriber's calling mechanism, an induction-coil, a lock-out magnet connected in shunt or parallel with a winding of said coil, subject to control by other subscribers, and impulse-transmitting means responsive to the operation of said mechanism.

12. A subscriber's calling mechanism, an induction-coil, a lock-out magnet connected in shunt or parallel with the primary winding of said coil, subject to control by other subscribers, and impulse-transmitting means responsive to the operation of said mechanism.

13. A subscriber's calling mechanism, an induction-coil, a telephone transmitter connected in series with the primary of said coil, a lock-out magnet connected in parallel or shunt with the said transmitter and primary, subject to control by other subscribers, and impulse-transmitting means responsive to the operation of said mechanism.

14. In a telephone exchange system, the combination of automatic means having vertical and rotary motion for trunking between calling and called subscribers, a telephone line, a plurality of calling dials on said line, a common battery for furnishing switching and talking current to said line,

- means for bridging the battery across the line, a locking magnet for each dial, and means for preventing bridging of the battery across the said telephone line until after the line calls or is called, said magnets bridged across the line. 5
15. In a telephone system divided into groups, a subscriber's calling dial, a telephone line, a dial-locking magnet bridged across the line, a common battery, means responsive to said dial for selecting groups by vertical motion and finding lines by rotary motion, and means for bridging said battery across the line to energize said magnet. 10
16. In a telephone system divided into groups, a subscriber's calling dial, a telephone line, a telephone bridged across the line, a dial-locking magnet bridged across the line, a common battery, means responsive to said dial for selecting groups by vertical motion and finding lines by rotary motion, and means for bridging said battery across the line to charge the telephone and energize said magnet. 15
17. In a telephone system divided into groups, a subscriber's telephone, a calling dial associated with said telephone, a telephone circuit, means responsive to said dial for selecting groups by vertical motion and finding lines by rotary motion, and a dial-locking magnet connected in a parallel branch or shunt of said circuit. 20
18. In a telephone system divided into groups, a subscriber's rotatable calling dial, means responsive to said dial for selecting groups by vertical motion and finding lines by rotary motion, an induction-coil, and a dial-locking magnet connected in shunt or parallel with a winding of said coil. 25
19. In a telephone system divided into groups, a subscriber's rotatable calling dial, means responsive to said dial for selecting groups by vertical motion and finding lines by rotary motion, an induction-coil, and a dial-locking magnet connected in shunt or parallel with the primary winding of said coil. 30
20. In a telephone system divided into groups, a subscriber's rotatable calling dial, means responsive to said dial for selecting groups by vertical motion and finding lines by rotary motion, an induction-coil, a telephone transmitter connected in series with the primary of said coil, and a dial-locking magnet connected in parallel or shunt with the said transmitter and primary. 35
21. In a telephone system divided into groups, a subscriber's rotatable calling dial, an induction-coil, a dial-locking magnet con-
- nected in shunt or parallel with a winding 60 of said coil, means responsive to said dial for selecting groups by vertical motion and finding lines by rotary motion, and a common battery or centralized source of talking current for energizing said magnet. 65
22. In a telephone system divided into groups, a subscriber's rotatable calling dial, an induction-coil, a dial-locking magnet connected in shunt or parallel with the primary winding of said coil, means responsive to 70 said dial for selecting groups by vertical motion and finding lines by rotary motion, and a common battery or centralized source of talking current for energizing said magnet. 75
23. In a telephone system divided into groups, a subscriber's rotatable calling dial, an induction-coil, a telephone transmitter connected in series with the primary of said coil, a dial-locking magnet connected in parallel or shunt with the said transmitter and primary, means responsive to said dial for selecting groups by vertical motion and finding lines by rotary motion, and a common battery or centralized source of talking current for energizing said magnet. 80
24. In a telephone system divided into groups, a subscriber's calling mechanism, means responsive to said mechanism for selecting groups by vertical motion and finding lines by rotary motion, an induction-coil, and a lock-out magnet connected in shunt or parallel with a winding of said coil. 90
25. In a telephone system divided into groups, a subscriber's calling mechanism, means responsive to said mechanism for selecting groups by vertical motion and finding lines by rotary motion, an induction-coil, and a lock-out magnet connected in shunt or parallel with the primary winding 95 of said coil. 100
26. In a telephone system divided into groups, a subscriber's calling mechanism, means responsive to said mechanism for selecting groups by vertical motion and finding lines by rotary motion, an induction-coil, a telephone transmitter connected in series with the primary of said coil, and a lock-out magnet connected in parallel or shunt with the said transmitter and primary. 105

Signed by me at Chicago, Cook county, Illinois, this 9th day of November, 1906.
